(57) **CLAIM**

The ornamental design for a detergent inlet for washing machine, as shown and described.

DESCRIPTION

1. Detergent inlet for washing machine
1.1 is a perspective view of a detergent inlet for washing machine, showing our new design;
1.2 is a front elevation view thereof;
1.3 is a rear elevation view thereof;
1.4 is a left-side elevation view thereof;
1.5 is a right-side elevation view thereof;
1.6 is a top plan view thereof;

(Continued)

1.7 is a bottom plan view thereof; and,

1.8 is a perspective view thereof, in a use condition.

The broken line shown in figure **1.8** is included for the purpose of illustrating environment and forms no part of the claimed design.

1 Claim, 8 Drawing Sheets
